EDWIN L. GREEN, OF CROSS PLAINS, TEXAS; CORDELIA A. GREEN, ADMINISTRATRIX.

TURNING GUIDE FOR FISHING TOOLS.

Application filed December 28, 1925. Serial No. 77,952.

This invention relates to improvements in fishing tools for reclaiming lost drill tools and bits which become detached in wells during the drilling thereof.

In the drilling of oil wells thru rock or other hard material, the bits or tools very often become misplaced. As the lower end of the bit has formed a cavity in the hard rock or material, at the bottom of the well, the lower end of the bit will ordinarily be properly positioned in alignment with the axis of the well. However, very often cavities exist above the lower end of the bit, and permit the latter to tip over and fall into the cavity, so that the upper end of the bit is out of alignment with the well, and conventional slip sockets cannot of course be used for catching the bit in order to "fish" the same from the well. It is therefore a primary object of this invention to provide a novel type of fishing tool, which may preferably be termed a turning guide for use in connection with conventional slip sockets or other fishing equipment, the function of which is to take hold of the bit which is inclined out of alignment with the well, and to straighten the said bit so that it may be caught by the socket or other fishing equipment and readily lifted to the ground surface.

A further object of this invention is the provision of a novel type of bit straightening guide for fishing equipment of oil wells, which may be used as an attachment for or as a part of the conventional slip socket, and embodies a novel hook below the socket for attaching the bit and facilitating the straightening thereof into axial alignment with the well, so that the socket may act thereon.

A further object of this invention is the provision of a preferably cylindrical shaped hollow guide for use in connection with fishing tools, adapted to be slipped over the conventional slip socket, and embodying a novel type of spiral shaped hook, of shell-like formation, below the socket, constructed in order to enable the most efficient catching of the bit and the straightening of the same into alignment with the well.

Other objects and advantages of this invention will be apparent during the course of the following detailed description.

In the accompanying drawing, forming a part of this specification, and wherein similar reference characters designate corre-

sponding parts throughout the several views,

Figure 1 is a sectional view taken through a well, showing a lost bit in the bottom of the well, inclined from the lower end of the well upwardly into a cavity at the side of the well, and showing the improved turning guide as used in connection with a fishing tool, to effect the straightening of the bit to permit its withdrawal from the well.

Figure 2 shows the improved tool in cross section, showing its application upon a socket, and showing the same having straightened a lost bit into vertical position and caught by the socket in order that the bit may be readily lifted to the ground surface.

Figure 3 is a perspective view of the improved turning guide or bit straightening tool.

Figure 4 is a bottom plan view of the improved tool.

In the drawing, wherein for the purpose of illustration is shown only a preferred embodiment of this invention, the letter A may generally designate the improved turning guide or fishing tool, which may be used as an attachment or as a part of the conventional fishing tool or slip socket B, for the purpose of reclaiming lost bits D or other drilling equipment in the well; the fishing tool B being connected by suitable string or supporting stem C extending upwardly thru the well and by means of which the improved tool A and the socket B may be turned to perform the functions hereinafter described.

The bit D is of the conventional form, including a body 10, having a lower drill end or base 11, which is diametrically wider than the diameter of the body 10, and which during drilling in hard rock 12 provides a bore or recess 13. Very often incident to the drilling of rock, as above mentioned, the drilling tool or bit will become disconnected from the drilling line, and the upper end 14 of the bit D will drop laterally into pockets or recesses 15, which quite frequently occur in wells, so that the upper end 14 of the bit D is out of alignment with the bore 17 of the well, but the lower end of the bit D incident to resting in the opening or recess 13 is properly in alignment with the bore 17.

The ordinary slip socket B includes a hollow body 20, suitably connected at its upper end by coupling means 21 with the fishing

line or string C. The socket opening in the lower end of the slip socket B faced downwardly, and in this opening slips 22 of any approved arrangement are provided, which are adapted to grip the upper end 14 of the drill bit D, as the socket is lowered into place for fishing the bit from the well. Quite frequently in connection with sockets, radial bolts 25 are provided at the lower end of the socket, for the attachment of a bowl or other equipment, and in connection with the improved type of guide A, these bolts 25 are important to effect its attachment to the socket B. The upper end of the body 20 of the conventional slip socket B is tapered, as at 27, or is provided with a shoulder which aids in supporting the improved turning guide A, when the latter is used as an attachment for conventional slip sockets B.

20 Referring to the improved turning guide or fishing tool A, the same is preferably in the form of a cylindrical shaped hollow shell, the same being of metal, the walls of which may be one-half inch in thickness, more or less, depending upon the type of equipment used, and the size of the well being drilled. It comprises a hollow body portion 30 of cylindrical shaped formation, said body portion 30 having an upper tapered end 31 tapering inwardly with diminishing diameter, and adapted to provide a supporting collar for seating on the tapered end or shoulder 27 of the conventional socket B, with the socket B received in the passage-way 33 within the body 30. The body 30 at diametrically opposed points is preferably provided with elongated slots 35, which are beveled inwardly, and which slots 35 when the socket B is received therein, lie 35 in alignment with the similarly positioned slot 36 of the socket B, to have access to the equipment of the socket B. At the lower end of the body 30 of the tool A, countersunk openings 38 may be provided, thru 40 which the bolts 25 above mentioned may be extended; the heads of the said bolts 25 being adapted to lie in the openings 38, in order to secure the lower portion of the tool body 30 to the socket B, as illustrated in 45 Figure 1 of the drawings. Thus, the body 30 is anchored at its upper end to the socket B to prevent its downward movement over the socket B, and the bolts 25 anchor the body 30 of the tool A to the lower portion 50 of the socket B, to prevent relative movement of the turning guide A and socket B in opposite directions.

The body 30 may be considered as terminating flush with the lower edge 40 of the slip socket B, and below this plane the improved turning tool A includes a bit guide hook 45, comprising the essential novelty of this invention, formed in a special cooperative relation with respect to the construction and location of a lost bit in the

well, to facilitate the straightening of the bit D to a vertical position where the same may be caught in the socket B.

The hook 45 of the tool A may be referred to as a spiral shaped hook, and it may be termed a sheet-like hook, in contradistinction to the round wire or spiral hooks used in this and other arts. The hook 45 at its extreme upper end is segmental in cross section, comprising a segment of substantially 180°, and it is connected flush with the body 30, at the lower end thereof. The hook 45 from the upper end thereof at 51 to the lower pointed end 50 thereof spirals through but one complete revolution. The hook 45 at its upper end is connected to the lower end of the body 30, from the point 51 to the diametrically opposed point 52, the segmental dimension of this upper end of the hook, as above mentioned being 180°, so that the opposite side of the hook, from the point 51 towards the point 52, is open to permit access of the bit D to the socket. The pointed end 50 of the hook 45 lies directly below the point 51, in a line measured parallel with the tool A, and from the lower pointed end 50 the lower edge 54 of the hook 45 inclines upwardly on a small pitch, to the point 55 which is diametrically opposed to the pointed end 50. From this location 55, to the point 51, the remaining portion 57 of the lower edge of the hook, slopes upwardly in spiral manner, on a pitch which is considerably steeper than the pitch of the lower edge 54 from the location 50 to the location 55. The lower edge portion 57 of the hook from the location 55 to the location 51 extends thru a spiral of 180°, and of course extends thru the major length of the hook 45, since the vertical distance from a plane intersecting the point 50 to a plane intersecting the point 55 is very small in comparison to the total height of the hook 45. The upper edge 60 of the hook 45 spirals upwardly thru an arc of substantially 180° from the point 50 to the point 52 which is diametrically opposed to the point 51. Thus, the upper and lower edges of the hook may be said to terminate in a horizontal plane, at diametrically opposed points, just below the lower edge of the socket B. The hook 45 increases in height from the point 50, measured on a vertical line, and the hook is of greatest height at the rear wall thereof, from the point 55 to the upper terminal 52 of the top edge 60 of the hook, as can readily be understood from Figure 3 of the drawings.

From the foregoing description of the shape of the hook 45, it can readily be understood that the upper edge of the hook 45 is spirally beveled thru an arc of 180° from the point 50 to the point 52, and spirally beveled as to its lower edge 57 from the point 55 to the point 51, thru substan-

tially 180°. Thus, the hook 45, at any horizontal plane of intersection thereof, is in the form of a half circle, or segment of 180°, and furnishes a spiral shaped opening which 5 spirals thru 180° throughout the length of the hook. This opening provided by the hook, 45, at the lower end of the hook is opened between the pointed end 50 and the lower location 55, and the opening spirals 10 upwardly thru 180° thru the length of the hook, the upper end of the opening extending from the location 51 to the location 52 below the edge 40^a, and facing in diametrically opposed direction to the opening at 15 the lower end of the hook 45, as can readily be understood.

Referring to the operation of placing the bit C, in order that the same may be elevated, the turning guide or tool A is placed 20 over the socket B, in the relation above described, and the socket is screwed to the pipe or string C and lowered into the well until the turning guide or tool A at its pointed end of the hook 45 engages against the bit 25 D in substantially the relation illustrated in Figure 1. The operator at the top of the well then takes a pipe wrench and secures the same to the string C, or by analogous means the string C to which the tool A is 30 rigidly connected is turned thru a slight arcuate movement, in order to thread the lower pointed end of the hook 45, so to speak, about the body of the bit D; the bit D riding upwardly into the spiral opening 35 provided by the hook 45, being guided into place by the upper edge of the hook 45 and stabilized in its position incident to the formation of the hook. When the hook 45 has been slipped to engage about the lower end 40 of the body of the bit D, the guide or tool A is drawn upwardly by elevation of the pipe or string C, which has the effect of pulling the inclined upper portion of the body of the bit D towards the center of the well 45 bore, and this operation is continued until the bit D incident to its engagement by the hook 45, and the weight of the bit D is vertically arranged in axial alignment with the well bore. The guide is then turned about 50 a half turn and the socket lowered until the slips of socket B engage the top of the bit D. The improved fishing tool is then elevated, with the bit D secured thereby.

From the foregoing description of this invention it is apparent that a novel type of bit guiding tool for fishing equipment has been provided, which is novel in its application and operation in the straightening of bits for the proper attachment thereof. The hook 45 may be provided with either a right or left spiral, and the tool A may either be used as an attachment for slipping over a socket B, or may be formed integral, welded or forged to any type of socket or fishing 55 tool.

Various changes in the shape, size, and arrangement of parts may be made to the form of invention herein shown and described, without departing from the spirit of the invention or the scope of the claims. 70

I claim:

1. In a guide for fishing tools the combination of a body, and a lower depending spiral shaped hook of shell-like formation, having a lower end substantially tapered to 75 a point, the upper edge of said hook from said point of the hook spiralling upwardly thru substantially 180° and the lower edge of said hook inclining downwardly from the upper end of said hook in spiral relation 80 thru substantially 180° to a point of termination 180° away from the free lower end of said hook, the upper ends of the upper and lower edges of said hook terminating at substantially opposed points, whereby to 85 provide a substantially spiral shaped opening forming a spiral of substantially 180° throughout the length of the hook, the width of said opening to the inside of the hook 90 being equivalent to the diameter of said hook.

2. As an article of manufacture a guide for fishing tools comprising a body, and a depending substantially spiral shaped hook spiralling thru substantially one revolution 95 only throughout the length thereof, said hook having a lower pointed end and having a lower edge spiraled upwardly on a shallow pitch from the lower pointed end to a point on the lower edge of the hook 100 180° away therefrom; the lower edge of said hook from said last mentioned point to the upper end of the lower edge spiralling at an increased pitch to the upper terminal of said lower edge which is directly vertically over the lower pointed end of said hook, the upper edge of said hook spiralling upwardly thru 180° from the pointed end of the hook to an upper terminal diametrically opposed to the upper terminal of the lower 110 edge of said hook.

3. In combination with a fishing tool slip socket having an upper shoulder, and a guide attachment for the socket including a cylindrical body portion having an upper retaining flange for seating on the shoulder of said socket, said hollow cylindrical body portion extending along the socket and at its lower end terminating at the lower end of said socket, said attachment including a substantially spiral shaped hook attached at the lower end of said hollow cylindrical body portion and extending below the socket and defining substantially a complete revolution and providing a substantially spiral shaped opening in the side thereof of sufficient width to receive the body of a bit therein to facilitate its straightening into axial alignment with the socket. 120 125

4. In a turning guide for fishing tools 130

the combination with a slip socket having an upper shoulder thereon, a turning guide including a hollow cylindrical shaped body portion adapted to be slipped over said socket and having a retaining flange upwardly thereof for seating on the shoulder of said slip socket, said hollow cylindrical body portion at the lower end thereof having openings therethrough, bolts transversely connected in said openings and extending into said socket for connecting the hollow cylindrical shaped body portion to the socket, said turning guide including a substantially shell-like spiral shaped bit receiving hook at the lower end thereof projecting below the slip socket and having the free end thereof at the lowermost point to

facilitate its slipping about the body of a detached bit, said spiral shaped hook providing a spiral shaped opening therein capable of receiving the body of the bit to facilitate its vertical alignment with said slip socket. 20

5. As an article of manufacture a turning guide for fishing tools comprising a hollow substantially cylindrical shaped body having a passageway therethrough, said body at the top thereof being upwardly tapered in a converging relation to restrict the passageway, and the passageway at its restricted portion extending through the top of said body, and a shell-like spiral hook on the lower end of said body. 25
